UNITED STATES PATENT OFFICE.

HORATIO G. CRESS, OF TROY, OHIO.

GAME.

1,338,493.

Specification of Letters Patent. Patented Apr. 27, 1920.

Application filed May 5, 1919. Serial No. 294,833.

To all whom it may concern:

Be it known that I, HORATIO G. CRESS, a citizen of the United States, residing at Troy, in the county of Miami and State of Ohio, have invented certain new and useful Improvements in Games, of which the following is a specification, reference being had therein to the accompanying drawing.

This invention relates to a game known 10 as Ko Ko and consists in a game of points, and is played with cards having relative numerical values, in combination with a diagram or chart upon which various positions and courses of movements are indicated; 15 suitable blocks or disks being used to indicate the movements upon the chart as the same are determined by the cards as the game progresses.

A color scheme is employed in connection 20 with the chart, certain of the cards and the blocks, known as men, whereby the relative positions of the chart, and the points of the game may be readily determined.

Referring to the drawings, Figure 1 illustrates the chart, showing in shaded lines the color scheme which is a feature of the game;

Figs. 2, 3, 4, 5 and 6 illustrate the number cards used in the game;

30 Fig. 7 illustrates the Ko Ko or master card being the card of highest value or privilege;

Fig. 8 illustrates one of the blocks or men used for indicating the progress of the game 35 on the chart.

The chart consists of a central design 1, having four color spaces 2, 3, 4 and 5 known in the game as "dens," each den being in a color different from the other dens and 40 agreeing in color with one of the "men."

Adjacent the sides of the chart, at the central portions thereof, are spaces known in the game as "homes" indicated in the drawing, as here shown, by castles having 45 the reference numeral 6, and which are also preferably in colors agreeing with the color scheme of the chart but having no significance or meaning in the game.

Starting at the four corners of the chart 50 in spaces designated by the letter A and terminating in the spaces occupied by the castles are circuitous routes 7, 8, 9 and 10

which are traversed in the game by the "men" of the players.

The routes 7, 8, 9 and 10 are divided into 55 blocks or steps of substantially equal spacing with certain of the blocks in a distinctive color, indicated in the drawings as red, and bearing a certain relation to the points of the game as will presently be described.

At the intersecting lines of the routes, designated in the game as "crossings" 11, 12, 13 and 14, four color blocks come together and constitute another feature of the 65 game that will be explained in connection with the instructions for playing.

The playing cards consist of four sets of 70 six cards to a set, five of the cards having numbers 1, 2, 3, 4 and 5, respectively, and the sixth card being the Ko Ko card, or card of highest value in the set. The cards preferably are in colors agreeing with the color scheme of the chart, but having no significance in the game.

The four men used in the game are preferably in four different colors, each man agreeing in color with one of the dens 1, 2, 3 and 4 of the chart.

The game of Ko Ko permits of variations 80 from any given set of rules for playing, but the following rules have been found well adapted to render the game most interesting to players young and old.

Rule 1.—The game may be played by 85 either two, three or four persons, each player using one of the four pieces we shall call men, and four sets of number cards. The player should choose the piece with color corresponding with that of the den in the 90 center of the game board next to his right. This enables the players to distinguish quickly to whom the different men belong. Partners will sit opposite each other. To begin playing each player will place his 95 man on the center of the curve A at his right, from which position the man will be moved along the circuitous route to his home at the other end of the road. The movements of the pieces or travelers are governed by the numbers on the cards and the Ko Ko card.

The cards are then placed in the center of the game board and each player draws a

card from the top. The player drawing the Ko Ko or largest number card plays first. If there is a tie, the drawing is repeated. The cards are then shuffled and dealt six 5 cards to each person when four players are in the game or twelve cards to each person when only two players are in the game. The cards are played alternately, face up on the player's home. The player moves his 10 man forward as many spaces as the card he plays indicates, but he must land on every red station. When a player cannot play forward he must play backward. Should a 15 player's card call for a station beyond the red station when playing backward, he must land on the red station. No playing backward is permitted from red stations or crossings, nor farther in either direction than the next red station. The Ko Ko card is a 20 card of privileges and allows the player to move his man to the next red station in either direction. If a player can land his man on his opponent's man, occupying a crossing, he removes his opponent's man to 25 the den. The player's man thus removed cannot be returned until he plays a Ko Ko card which entitles him to return his man to the red station from which he was removed. When all cards are played they are 30 divided as before and the playing continues. The Ko Ko card alone takes the player home from his last red station, when he has "kokoad" the other players and won the game.

35 *Rule 2.*—By slight changes in the rules the game may be made quite easy and well suited for very small children. As soon as children can count numbers they will be interested in playing the game as follows: 40 Remove the four Ko Ko cards, and then after shuffling the cards, lay them in the center of the game board, face down. The players then draw from the top and move their men forward, according to the number of the card, in the same manner to begin with as in Rule No. 1. All spaces on 45 the road are counted and the player's man jumps to the station indicated by his card. The game is won by the player who reaches 50 home first.

55 *Rule 3.*—The game is made a little more difficult than No. 2 by playing in the same manner, but the player must continue to draw until he gets a card that will land him on every red station or crossing. The game is won in the same manner as in Rule No. 2.

60 *Rule 4.*—To teach subtraction as well as counting and adding the players begin as in Rule No. 1, but each player holds his cards face down; to determine the move, he draws the card from beneath and places it face up on the top, the player moving his man as far as his card indicates, except that he may not go beyond the next red station. When

he has drawn his second card and it is less 65 than the first number he has drawn, he must move backward the difference between the two numbers, but not farther than the next red station. If it is larger than the first card drawn, he moves his man forward the 70 number of spaces indicated on his card or the distance indicated by the sum of the two numbers, but he cannot move forward should neither of the two numbers indicate a movement farther than the next red station or crossing. When the cards are all 75 face up they are again shuffled and distributed and the game continues and is won in the same manner as by the other rules.

Having thus fully described my invention, 80 what I claim as new and desire to secure by Letters Patent, is:—

1. In a game, a diagram comprising a plurality of dens and a corresponding plurality of homes, circuitous routes leading to said 85 homes, steps and stations upon said routes, men traversing said routes, and number cards to determine the direction and extent of movement of said men.

2. In a game, a diagram comprising a plurality of dens in different colors and a corresponding plurality of homes, circuitous routes leading to said homes, steps and stations upon said routes, men in different colors, agreeing with the colors of said dens, 95 traversing said routes, and number cards to determine the direction and extent of movement of said men.

3. In a game, a diagram comprising a plurality of dens representing adverse points 100 of the game, and a corresponding plurality of homes representing the objectives of the game, a circuitous route leading to each of said homes and having steps, stations and crossings thereon representing points of the 105 game, a man traversing each of said routes toward and away from said home and subject to movement into one of said dens, and number cards to determine the direction and extent of movement of each man.

4. In a game, a diagram comprising a plurality of central dens representing adverse points of the game, and a corresponding plurality of marginal homes representing the objectives of the game, a circuitous route 115 leading from each corner of the diagram to one of said homes and having steps, stations and crossings thereon representing points of the game, a man traversing each of said routes toward and away from said 120 home and subject to movement into one of said dens, and number cards to determine the direction and extent of movement of each man.

5. In a game, a diagram comprising a plurality of dens in different colors and representing adverse points of the game, a corresponding plurality of homes each corre- 125

sponding in color to one of said dens and representing the objectives of the game, routes leading to each of said homes and having steps, color stations and intersecting 5 color crossings arranged thereon and representing point values of the game, a man traversing each of said routes toward and away from one of said homes and subject

to movement into one of said dens, and number and master cards agreeing in colors with 10 said dens and homes to determine the direction and extent of movement of each man.

In testimony whereof, I affix my signature.

HORATIO G. CRESS.
